H. T. KRAFT.
REINFORCED RUBBER PROPELLER,
APPLICATION FILED JUNE 29, 1917.

Patented June 6, 1922.

UNITED STATES PATENT OFFICE.

HERMAN T. KRAFT, OF AKRON, OHIO, ASSIGNOR TO THE GOODYEAR TIRE & RUBBER COMPANY, OF AKRON, OHIO, A CORPORATION OF OHIO.

REINFORCED RUBBER PROPELLER.

1,419,061.

Specification of Letters Patent. Patented June 6, 1922.

Application filed June 29, 1917. Serial No. 177,721.

To all whom it may concern:

Be it known that I, HERMAN T. KRAFT, a citizen of the United States, residing at Akron, in the county of Summit and State 5 of Ohio, have invented new and useful Improvements in Reenforced Rubber Propellers, of which the following is a specification.

My present invention relates to air craft 10 propellers, and more particularly relates to a novel propeller construction seeking to displace the usual laminated wooden type now universally employed.

The laminated wooden propeller, while 15 having great strength and lightness, is open to a number of disadvantages in actual practice. Among these are the fact that glued wooden propellers are not proof against the action of the elements, which causes their 20 premature deterioration. Another is that when a propeller blade is broken during the use of the air craft, the flying fragment is apt to encounter the gas bag, aeroplane surface, guy wires or other portions of the craft 25 and do severe direct damage. It may be noted in this connection that a number of 30 dirigible accidents are directly traceable to the fact that a broken propeller blade was thrown with such force against the gas bag as to puncture the envelope and destroy the 35 balloon. In addition to the direct damage wreaked by a broken blade part, the unbalanced force created by rotation at high speed of the remaining propeller part tends 40 to tear the motor from its foundations.

A still further disadvantage of the laminated all-wood propeller resides in the fact 45 that it is liable to split and splinter, either when used under enemy rifle fire, or by reason of some flaw or inherent defect in the wood which the stress of usage suddenly develops, or the almost incredible abrading action of spray when the propeller is used on a hydroplane. Not only do splintered out 50 places proportionally weaken the blade, but the flying splinters are a menace to the safety of the aviator and his craft.

As a principal object of this invention, 55 accordingly, it is proposed to provide a propeller blade so constructed that it will be proof against water and dampness; that it will be non-splinterable; and that it will be so reenforced as to prevent the throwing off of any pieces or parts of the blade.

The above and additional objects of a

similar nature, which will be hereinafter more specifically treated, may be accomplished by such means as are illustrated in the accompanying drawings, described in the following specifications and then more 60 particularly pointed out in the claims which are appended hereto and form a part of this application.

With reference to the drawings, wherein there has been illustrated a preferred embodiment of the invention as it is reduced to practice, and throughout the several views of which, similar reference numbers designate corresponding parts:

Fig. 1 is a perspective view of a propeller 70 blade constructed in the manner set forth in the present invention;

Fig. 2 is a partial perspective view of the propeller blade of Fig. 1;

Fig. 3 is a plan view of one of the novel 75 types of propellers proposed herein with a modified form of interior reinforcement;

Fig. 4 is a fragmentary elevational view of a propeller blade in which the rubber is used as a veneer upon a laminated wooden 80 reinforcement;

Fig. 5 is a fragmentary view of a propeller blade having a reticulated metal reinforcement;

Fig. 6 is a cross sectional view on the line 85 6-6 of Fig. 4;

Fig. 7 is a fragmentary elevational view of a propeller blade showing various types of 90 metallic reinforcement which may be employed; and

Fig. 8 is an elevational view of a framework which may desirably form the interior reinforcement for a propeller blade otherwise constructed wholly of rubber.

The material I have chosen to form the 95 basis for the novel departure in propeller construction proposed herein is rubber, either used solidly with suitable interior reinforcements or used as a veneer upon laminated wooden propellers. A propeller built up of reinforced rubber or constructed of a rubber veneered material is proof against the action of dampness; has no tendency towards splintering when impinged upon by a small object during its rapid revolution; can be 100 constructed with a resistance to discharging broken pieces at a tangent; and, although somewhat heavier than a corresponding wooden propeller, the improved propeller possesses an equal or greater strength.

It is well known that rubber possesses the property of undergoing such a molecular change during vulcanization that it loses that property of resiliency which is so popularly associated with the term "rubber". Some desirable rubber compound or other compounds may be utilized which will cure hard and which have, preferably, a low specific gravity.

- 10 One of the simple forms which my invention may take is illustrated in Figs. 1 and 2 in which the propeller blade as a whole is molded over a number of interiorly grouped rod or strip reinforcements 10. These rods 15 may be of any material which will provide the desired reinforcement for the rubber propeller blade, and may be of such dimensions as good mechanical practice dictates in the actual working of my invention. They may 20 also be straight from hub to blade-tip, or may be shaped as desired to the propeller curvature. In order to provide a firm union between the hard rubber covering and interior reinforcements, I may resort to the 25 twisted, braided, or plaited wire bands 10 disclosed in Fig. 3. These bands may be so proportioned as to provide the right amount of inner reinforcement while at the same 30 time be so constructed that the rubber may enter and penetrate the bands through the interstices of the twisted or plaited wires, in much the same manner that rubber is used to make a union with the braided wire beads of an automobile tire.
- 35 My present invention is, however, not limited to the types of reinforcement illustrated, as I may have resource to the employment of a laminated wooden blade 12 such as is illustrated in Figs. 4 and 6, this blade being 40 smaller than the desired dimensions of the finished propeller in order to permit of a substantial coating or veneer 13 of hard rubber upon the exterior of the inner blade. If 45 a laminated wood reinforcement is employed as thus suggested, I prefer to provide a number of apertures 14 through the wooden blade in order that the rubber may flow through and harden within these apertures in the manner denoted by numeral 15 of Fig. 6 to 50 provide a union between opposite faces of the veneer or coating 13.
- Again, I may have recourse to the employment of one or more strips of screen wire 16 to be used to interiorly reinforce the rubber 55 blade in the manner shown in Fig. 5, the rubber being vulcanized through the interstices of the screen in such a manner as to form a most advantageous binding together of the rubber mass.
- 60 A further modification of the underlying principle of this invention is disclosed in Fig. 7, a plurality of bars 17 being shown as located interiorly of the hard rubber mass to provide the desired strengthening elements. These bars may be of proper metal

and of a dimension varying with the depth of the rubber in which they are embedded. For instance, I may employ heavier bars in the center of the rubber mass and may use lighter bars or wires nearer the edges of the 70 rubber mass.

Again, without departing from the true scope of the present invention, I may employ a framework 18 of metal or a similarly appropriate material, such framework following the lines of the finished propeller shape and including, if so desired, longitudinals 19 which may be connected by cross rods or bars 20 in order to secure a reinforcing framework of sufficient strength. 75

In any case, I prefer to mold the propeller blades directly to shape and to vulcanize the molded rubber to secure that degree of hardness which is essential in an efficient blade. The descriptive wording "agglomerated material," set forth in the claims, should be construed to mean a material that is merely gathered together in a mold as distinguished from impregnated layers of material which are disposed in a mold with regard to the 80 sequence of the layers.

Among the advantages of the novel type of air craft propeller herein proposed, and not already enumerated, are those of rapidity, uniformity and relative cheapness of 95 manufacture. The proper rubber compounds may be evolved and mixed at no greater cost than is involved in the selection, drying, gluing, curing and the subsequent wasteful hand-turning and finishing of the 100 laminated wooden propellers now in practically universal use, while the process of molding my propeller blades makes for a vast saving in time of manufacture and offers a great gain in the uniformity of the 105 product.

With the use of a propeller of the type I have herein proposed, aerial navigation will be rendered much safer by protecting both the aviator and his craft from flying fragments of all too frequently broken blades. These cannot possibly be discharged by the propeller of my invention even when broken, as the internal reinforcement will obviously prevent. Moreover, my type of rubber covered and internally reinforced blade obviates the frequent necessity for repairs to split, splintered or otherwise damaged propellers. 115

What I claim is:

1. As a new article of manufacture, an air craft propeller including an interior reinforcing element composed of associated metal strands and a body of an agglomerated carbonaceous material molded to shape a 125 propeller upon the reinforcing element.
2. As a new article of manufacture, an air craft propeller constructed of an agglomerated carbonaceous material molded to shape upon interior reinforcing elements, said re- 130

inforcing elements comprising a plurality of metal elements associated to produce a unitary reinforcing element.

3. As a new article of manufacture, an air craft propeller constructed of rubber molded to shape upon an interior reinforcing member, said member comprising a plurality of metal strands associated in groups.

4. As a new article of manufacture, an air craft propeller constructed of rubber molded to shape upon an interior reinforcing member, said reinforcing element comprising a plurality of metal strands pressed to form a single cable.

15 5. A composite propeller blade comprising an interior reinforcing element composed of associated metal strands and a body of carbonaceous material molded to shape a propeller upon the reinforcing element and 20 vulcanized thereto.

6. A propeller blade comprising a heat hardened material molded to the shape of a propeller blade, reinforcing elements embedded in said material and individually 25 comprising a plurality of intermeshed metallic elements united to form a single cable, said cables being regularly arranged within said material and bonded therewith.

7. A body of rubber composition molded

to shape a propeller blade, metallic reinforcing strands arranged within said composition and each comprising a plurality of braided strands, said strands being disposed longitudinally of said blade in regular spaced relationship and vulcanized with said composition to establish bonding relation therebetween.

8. A propeller blade formed of an agglomerated moldable material embodying reinforcing metallic fibrous material embedded in the moldable material and bonded therewith in surface engagement.

9. A molded propeller blade embodying regularly arranged portions of metallic fibrous material and a heat hardened agglomerated material.

10. A propeller blade formed of an agglomerated plastic material having a plurality of regularly arranged reinforcing elements embedded therein and individually surrounded by the plastic material.

In testimony whereof, I have signed my name in the presence of two subscribing witnesses.

H. T. KRAFT.
